ATTY.

UNITED STATES PATENT OFFICE.

CHARLES EDWARD DOWSETT, OF DERBY, ENGLAND.

SPRING-MATTRESS.

1,367,950.

Specification of Letters Patent.

Patented Feb. 8, 1921.

Application filed January 22, 1919. Serial No. 272,411.

To all whom it may concern:

Be it known that I, CHARLES EDWARD DOWSETT, a subject of the King of Great Britain and Ireland, residing at 308 Nor-
5 manton road, Derby, in the county of Derby, England, have invented new and useful Im-
provements in Spring-Mattresses, of which
the following is a specification.

Referring to the drawings which form a
10 part of this specification Figure 1 is a plan
of a spring mattress showing the applica-
tion of my invention.

Fig. 2 is a section on line 3—3 of Fig. 1.

This invention relates to the type of
15 spring mattress in which bolts 4 are used
for tightening up the woven-wire part or
mattress proper 5 which is secured to a
piece 6 having longitudinal movement, and
through which the bolts 4 pass, project in-
20 ward thereof and under the wire work or
the like; the latter in course of time be-
comes worn by continually rubbing on said
bolts.

The object of my invention is to protect
25 the mattress and in carrying the same into
effect I fix suitably shaped shields or pro-
tectors 7 on the part 6 capable of longi-
tudinal movement or upon the under side
of the mattress 5 to lie between the latter

and the bolts. As shown herein, the shields 30
are formed of plates of sheet metal, which
plates are rounded or beveled at the corners
so that all of the angles formed by the inter-
secting edges of each of the plates are ob-
tuse angles, whereby the mattress is pro- 35
tected from contact with sharp corners. It
will also be observed that the plates are of
such length and so located as to at all times
present a portion of the plates between the
woven wire mattress and the stretching bolts 40
so as to prevent contact of the mattress with
the bolts.

Having now described my invention what
I claim as new and desire to secure by Let-
ters Patent is:—

In a woven wire mattress having means for
stretching the same, a plurality of protect-
ing shields comprising sheet metal plates,
the intersecting edges of each of said plates
forming obtuse angles thereby to prevent 50
contact of the mattress with sharp corners,
the plates being of such length and so lo-
cated as to at all times present a portion of
the plate between the mattress and its
stretching means.

In testimony whereof I have signed my
name to this specification.

CHARLES EDWARD DOWSETT.
